THREAD CUTTER AND CLAMP FOR WEFT REPLENISHING LOOMS

Joseph Miller, Worcester, Mass., assignor to Crompton & Knowles Loom Works, Worcester, Mass., a corporation of Massachusetts

Application January 23, 1943, Serial No. 473,353

9 Claims. (Cl. 139—264)

This invention relates to improvements in thread cutters and clamps for weft replenishing looms and it is the general object of the invention to provide an improved mechanism of this type which will hold the thread securely after cutting incident to a weft replenishing operation.

At the time of bobbin transfer in a weft replenishing loom a thread extends from the selvage to the shuttle under the magazine and to the depleted bobbin which is expelled from the shuttle during a transferring operation. Provision must be made to cut this thread and clamp it so that it will not be drawn into the warp shed when the shuttle is next picked. Cutters of the type to which my invention more particularly relates cut the thread between the shuttle box and the selvage and release the thread extending to the bobbin so that it can be moved out of the shuttle box by the descending depleted bobbin. The thread extending to the selvage, however, must be held out of the path of the shuttle until it can be severed by the temple cutter on a later pick. It is an important object of my present invention to provide an improved clamp so constructed as to bend as well as clamp the thread at a plurality of points for the purpose of holding the thread securely as it awaits cutting at the selvage.

Clamping plates have been used heretofore in connection with thread cutters for the purpose of forcing the cut thread against a surface of the cutter blade but it has been found in practice that with certain types of yarns this form of clamp does not hold the thread tightly enough to prevent it from slipping out of the clamp. It is another object of my invention to provide an auxiliary clamp additional to the primary clamp and construct both clamps so that they have clamping surfaces transverse to the main clampings surfaces for the purpose of bending the thread around corners which resist its removal.

It is a further object of my present invention to mount the primary clamp so that it can yield to and thus permit a close fit with the transverse surfaces of the auxiliary clamp. The yielding is permitted by a spring which exerts its force perpendicular to the force exerted by the spring which urges the main clamp and movable cutter toward the stationary cutter, hence these two springs do not interfere with each other.

It is a still further object of my invention to mount one of the cutters for a floating motion during movement of the other cutter, and provide the floating cutter with an end bent toward

the other cutter for the purpose of holding the cutting edges close to each other throughout the cutting operation.

With these and other objects in view which will appear as the description proceeds, my invention resides in the combination and arrangement of parts hereinafter described and set forth.

In the accompanying drawing, wherein a convenient embodiment of my invention is set forth,

Fig. 1 is a side elevation of a weft replenishing mechanism having my improved cutter and clamp applied thereto,

Fig. 2 is a diagrammatic plan view looking in the direction of arrow 2, Fig. 1,

Fig. 3 is an enlarged vertical section on line 3—3 of Fig. 1,

Fig. 4 is a rear elevation of the cutter and clamp on an enlarged scale looking in the direction of arrow 4; Fig. 1,

Figs. 5 and 6 are diagrammatic views showing the cutter and clamp in different positions.

Fig. 7 is a detail horizontal section on line 7—7, Fig. 4, and

Fig. 8 is an enlarged vertical section on line 8—8 of Fig. 5 showing the manner in which the clamp holds the severed thread.

Referring particularly to Figs. 1 and 2, I have shown a loom frame 10 on which is mounted a magazine M preferably of the multicolor type and having a rocking shaft 11 to which is secured an arm 12. A link 13 descending from the arm is connected to a lever 14 movable about a stud 15 carried by a stand 16 bolted or otherwise secured to the magazine frame. The lever 14 carries a stud 17 on which is mounted a cutter and clamp carrier arm 18 having a rear finger 19 to abut a shoulder 20 on the lever 14. A forward finger 21 of arm 18 receives the forward thrust of a compression spring 22 housed in a pocket 23 formed in the lever 14. The spring and stop shoulder serve normally to hold the parts in the position shown in Fig. 1 but permit movement of the arm 18 forwardly, or to the right as viewed in Fig. 1, relatively to the lever 14.

A yielding lock designated generally at L includes a spring 24 which tends to hold the shaft 11 and arm 12 in either of the two extreme positions to which they move during a replenishing operation. A rod 25 passes through a swivel bearing 26 pivoted at 27 on the stand 16 and having top and bottom collars 28 and 29, respectively. A spring 30 between the swivel bearing 26 and the bottom collar 28 exerts a normal downward force on the rod 25 to hold it as shown in Fig. 1.

The lay 32 is provided with a shuttle box 33 for a shuttle S which, as shown in Fig. 2, has a bobbin 34 therein from which thread T extends inwardly to the selvage of the fabric F which is held spread by a temple 35 having the usual temple cutter 36. The loom is provided with the usual transfer mechanism not shown for moving a reserve bobbin from the magazine into the depleted shuttle and at the same time driving the depleted shuttle 34 out of the shuttle.

The matter thus far described operates in the usual manner at the time of a replenishing operation. The link 13 is normally down so that the carrier arm 18 and the cutter and clamp mechanism thereon designated at C are in forward position. When a replenishing operation occurs, arm 12 rises and causes link 13 to rock lever 14 in a clockwise direction as viewed in Fig. 1 around stud 15 for the purpose of moving the mechanism C rearwardly toward the lay, or to the left as viewed in Fig. 1. During this rearward movement the top collar 28 prevents downward motion of the lower end of rod 25 and since the studs 15 and 27 are offset horizontally there is a differential motion between the structure C and the bottom of the rod 25. As the lay nears its forward position it moves the cutter and clamp forwardly to reset the parts to their normal position, and at some subsequent forward beat of the lay the temple cutter 36 will cut the thread T at the selvage.

The matter thus far described is of common construction and for further description reference may be had to prior Patents Nos. 1,261,417, 1,610,562 and 1,633,648.

In carrying my present invention into effect, I construct the cutter and clamp C substantially as shown in Figs. 3 to 8. The lower part of arm 18 is provided with a rearwardly extending foot 40 undercut as at 41 to receive a stationary cutter blade 42 having a lower cutting edge 43. As shown in Fig. 7 foot 40 has projecting laterally therefrom a pin 44 which enters a hole 45 in blade 42 and the forward end of the blade is curved at 46 away from foot 40. A stud 47 is threaded into foot 40 and held by lock nut 48 and passes through blade 42. The latter is floated on pin 44 and stud 47 and is not bolted directly to foot 40 as formerly. Pivoted on the stud 47 is a movable cutter blade 50 having an upwardly facing preferably straight cutting edge 51 to cooperate with edge 43. The forward end of the movable cutter is extended to provide an arm 52 carrying a stud 53 connected pivotally to the lower end of the rod 25.

A primary clamp plate 55 is pivotally mounted on the stud 47 and is forced toward the stationary cutter blade 42 by an arched leaf spring 56 held under the head 57 of stud 47. The primary clamp has an upstanding horn 58 which is offset as shown in Fig. 4 to pass upwardly in front of a stop pin 59 carried by foot 40. A tension spring 60 is connected to the primary clamp and also to a pin 61 fixed to the foot 40 and tends to move the horn 58 toward the stop 59 but permits the clamp 55 to turn in a clockwise direction as viewed in Fig. 6.

Heretofore the clamp 55 has been faced directly against cutter blade 50, but I provide an auxiliary clamp 65 pivoted on the stud 47 and extending along the pivoted cutter blade between the latter and clamp plate 55. This auxiliary clamp 65 is held in position by the stud 47 and 70 53 and moves angularly with the cutter blade 50. A foot 70 projects laterally from clamp 65 75

under the primary clamp and has an upwardly facing surface 71 to engage the downwardly facing surface 72 of clamp plate 55. The primary clamp is provided with a lug 75 fixed thereto and extending over the auxiliary clamp, and the latter has an upper edge 77 to engage the lower surface 78 of the lug 75 when surfaces 71 and 72 engage each other.

When the mechanism C is in its normal position shown in Figs. 1 and 5 the cutter blade 50 and clamp 65 are in their raised position and surfaces 71 and 77 are close to surfaces 72 and 78, respectively. Rod 25 exerts a downward force on stud 53 and holds horn 58 spaced slightly in front of pin 59. When the cutter C moves rearwardly as already described the rod 25 will cause angular movement of the blade 50 and the auxiliary clamp 65 relatively to blade 52 and clamp 55 to the position shown in Fig. 6. Pin 59 engages horn 58 during this operation and prevents clamp 55 from following clamp 65. The cutter is now open with the rear part of the movable jaw extending downwardly at an angle to form a notch for the reception of the thread T as the lay advances. Near the end of the forward movement of the lay the foot 40 is moved forwardly and the parts are returned to the position shown in Fig. 5 by a motion which causes the blade 50 and auxiliary clamp to turn in a clockwise direction relatively to the foot 40 as viewed in Fig. 6, thereby cutting the thread due to the interaction of edges 43 and 51.

During the closing of the cutter that part of the thread which extends between the cutter blades and the selvage of the fabric will be bent to the general position shown in Fig. 8. As clamp 65 rises it engages the thread and pushes it against clamp 55. Cutting edge 51 then forces the thread against edge 43 and cuts it. As the clamp 65 continues to rise it lifts the cut end of the thread and holds it between the two clamps. Near the end of the resetting operation surfaces 71 and 77 force the thread against surfaces 72 and 78, respectively, to produce bends in the thread, as shown in Fig. 8. To insure tight holding of the thread, rod 25 pushes down sufficiently to turn clamp 55 slightly, thereby moving horn 58 forwardly a slight distance from stop pin 59. The mechanism C is now fully reset as shown in Fig. 5, and the thread extends from the selvage between the surfaces 71 and 72, around the left lower corner of the primary clamp plate 55 as viewed in Fig. 8, upwardly between the primary and secondary clamps, and then to the left between surfaces 77 and 78 toward the stationary blade 42. The leaf spring 56 holds the cutter and clamping parts in close engagement with each other throughout the opening and closing operations. 60 The clamping of the thread is therefore effected partly by the leaf spring which creates frictional contact between the vertical surfaces of the primary and secondary clamps, and partly by the spring 60 which exerts pressure on the thread between the horizontal clamping surfaces.

The thread will eventually be cut at the temple, but will remain in the clamp as shown in Fig. 8 until the next replenishing operation of the loom, at which time opening of the cutter which accompanies rearward movement of the mechanism C will release the thread.

As the blade 50 swings from open to closed position that part of it to the right of stud 47 as viewed in Fig. 7 will slide along the offset or curved part 46 of blade 42 and cause edge 43 to

remain in close cutting contact with the moving cutter. The ability of blade 42 to float as already described together with the action of curved end 46 insures proper cutting of the thread wherever it may be located along the cutting edges.

From the foregoing it will be seen that I have provided a simple means by which the thread extending from the selvage to the thread cutter may be clamped effectively between primary and secondary clamps which serve to exert holding forces on the thread due to the vertical surfaces of the two clamps and also due to the horizontal cooperating clamping surfaces of the two clamps. It will also be seen that the thread is required to pass around two corners, a condition which assists materially in holding the thread in the clamp. Furthermore, it will be noted that the spring 60 urges the horizontal clamping surfaces against each other and does not interfere in any way with the action of the leaf spring in forcing the vertical clamping surfaces toward each other. Furthermore, the floating cutter blade 42 with its curved end 46 aids materially in the cutting operation.

Having thus described my invention it will be seen that changes and modifications may be made therein by those skilled in the art without departing from the spirit and scope of the invention and I do not wish to be limited to the details herein disclosed, but what I claim is:

1. In a thread clamp for a weft replenishing loom thread cutting mechanism having a carrier provided with a stationary and a movable cutter, a primary clamp on that side of the movable cutter opposite the stationary cutter, a secondary clamp moving with the movable cutter and located between the latter and the primary clamp, each clamp having a vertical and a horizontal surface for engagement with similar surfaces on the other clamp, and means to move the movable cutter to cut the weft and also cause the vertical surfaces of said clamps to slide relatively to each other to cause the horizontal surfaces of said clamps to approach each other and produce a bend in the thread extending from the movable cutter and between said clamps.

2. In a thread clamp for a weft replenishing loom thread cutter having a carrier provided with a stationary and a movable cutter blade, a primary clamp mounted on the carrier and having a vertical and a horizontal thread engaging surface, an auxiliary clamp moving with the movable cutter blade and having a vertical and a horizontal surface to engage the corresponding surfaces of the primary clamp, resilient means tending to force said clamps toward the movable cutter blade, and means to actuate the movable cutter blade to cut the thread and simultaneously move the auxiliary clamp relatively to the primary clamp to move the horizontal surfaces of the clamps relatively to and toward each other to produce a bend in and clamp the thread extending from the movable cutter blade and along said vertical surfaces.

3. In a thread clamp for a weft replenishing loom thread cutting mechanism having a carrier provided with a pivoted cutter, a primary clamp pivotally mounted on the carrier for movement in a plane parallel to the plane in which the pivoted cutter moves, a stop for said primary clamp, a spring to hold said primary clamp against said stop, an auxiliary clamp between the primary clamp and the pivoted cutter, said clamps hav-

ing adjacent vertical surfaces and also adjacent horizontal surfaces, means supported by the carrier to force the primary clamp against the auxiliary clamp, and means to move the pivoted cutter to cut the thread and also move the auxiliary clamp to cause the horizontal surface of the auxiliary clamp to exert a force on the horizontal surface of the primary clamp and move the latter against the action of said spring and away from said stop, the thread extending from the pivoted cutter being clamped between the adjacent vertical and horizontal surfaces of said clamps.

4. In a thread clamp for a weft replenishing loom thread cutting mechanism having a carrier provided with a stationary and a movable cutter, and a primary clamp located on that side of the pivoted cutter opposite the stationary cutter, an auxiliary clamp between the primary clamp and the pivoted cutter, means to mount both of said clamps for pivotal movement relatively to the carrier, a stop for the primary clamp, resilient means holding the primary clamp against said stop, said clamps having surfaces for mutual engagement substantially parallel to the planes in which said clamps move pivotally and having other surfaces for mutual engagement which are transverse of the planes in which said clamps move pivotally, and means to move the transverse surface of the auxiliary clamp against the thread extending between said clamps and force the thread against the transverse surface of the primary clamp sufficiently to move the latter against the action of said resilient means away from said stop.

5. In a thread clamp for the thread cutting mechanism of a weft replenishing loom having a carrier, a primary clamp pivotally mounted on said carrier, a stop on the carrier for said primary clamp, resilient means supported by the carrier to hold said primary clamp against said stop, an auxiliary clamp pivotally mounted on the carrier, said clamps having primary thread engaging surfaces substantially parallel to the planes in which the clamps move pivotally with respect to the carrier, resilient means to hold one of said primary surfaces against the other primary surface, and each clamp having a secondary thread clamping surface transverse of said planes to engage the corresponding transverse surface of the other clamp, and means to move the auxiliary clamp to cause the transverse surface thereof to transmit a force through a thread extending between said primary surfaces against the transverse surface of the primary clamp and cause the latter to move away from said stop against the action of said resilient means, the latter assisting said secondary surfaces to clamp the thread.

6. In a thread clamp for a weft replenishing loom thread cutting mechanism having a carrier provided with a movable cutter blade, a primary clamp mounted on the carrier and having vertically spaced horizontal thread clamping surfaces between which extend a vertical thread clamping surface, an auxiliary clamp pivotally mounted on the carrier and moving with the pivoted cutter blade and having vertically spaced horizontal thread clamping surfaces between which extend a substantially vertical thread clamping surface, means to mount the primary clamp on the carrier for pivotal movement, resilient means to hold the primary clamp in a given angular position with respect to the car-

rier, and operating means to move the auxiliary clamp and movable cutter blade in a direction to cut the thread and cause said horizontal surfaces of the auxiliary clamp to force a thread extending between said vertical surfaces against the horizontal surfaces of the primary clamp and move the latter against the action of said resilient means away from said given position and cause the resilient means to cooperate with said operating means to exert a holding force on the thread between the horizontal surfaces of said clamp.

7. In a thread clamp for a weft replenishing loom thread cutting mechanism having a carrier provided with a pivoted cutter blade, a primary clamp mounted on the carrier and having vertically spaced thread clamping horizontal surfaces between which extend a vertical thread clamping surface, an auxiliary clamp pivotally mounted on the carrier and moving with the pivoted cutter blade and having vertically spaced horizontal thread clamping surfaces between which extend a substantially vertical thread clamping surface, means to mount the primary clamp on the carrier for pivotal movement, resilient means to hold the primary clamp in a given angular position with respect to the carrier, and operating means to move the auxiliary clamp and pivoted cutter in a direction to cut the thread and cause the horizontal surfaces of the auxiliary clamp to force a thread extending between said vertical surfaces against the horizontal surfaces of the primary clamp and move the latter against the action of said resilient means away from said given position and cause the resilient means to cooperate with said operating means to exert a holding force on the thread between the horizontal surfaces of said clamp, said cutter blade and clamps having a common pivotal support on the carrier.

8. In a thread clamp for a weft replenishing loom thread cutter having a carrier provided with a stationary and a movable cutter blade, a primary clamp pivotally mounted on the carrier, an auxiliary clamp moving with the movable cutter blade in a given direction preparatory to a cut-

ting operation and cooperating with the primary clamp to clamp a weft thread when moving in the opposite direction, means on the primary clamp extending transversely of the plane of movement of the auxiliary clamp and over the auxiliary clamp for engagement with the latter and cooperating therewith to clamp the thread when the auxiliary clamp moves in said opposite direction, resilient means to hold the clamps against each other, and stop means on the carrier to limit angular movement of the primary clamp in said given direction when the auxiliary clamp and movable cutter blade move in said direction.

9. In a thread clamp for a weft replenishing loom provided with a weft thread to be cut by a thread cutter having a carrier provided with a stationary cutter blade and a second cutter blade pivoted thereto, a primary clamp mounted on the carrier for pivotal movement with respect thereto in a plane transverse of said thread, an auxiliary clamp pivotally mounted on the carrier and moving with the pivoted cutter blade substantially parallel to said plane, resilient means to force the primary clamp laterally against the auxiliary clamp to assist said clamps to hold a thread, operating means to move the pivoted cutter and auxiliary clamp relatively to the carrier in a given direction preparatory to a thread cutting and clamping operation and thereafter move said pivoted cutter and auxiliary clamp in the opposite direction to operate on the thread, a stop on the carrier to limit movement of the primary clamp when the auxiliary clamp moves in said given direction, a second resilient means tending to hold said primary clamp against said stop, and an element on said auxiliary clamp exerting a force on said primary clamp derived from said operating means to move the primary clamp away from said stop and against the action of said second resilient means when the auxiliary clamp approaches the end of the movement thereof in said opposite direction caused by said operating means.

JOSEPH MILLER.
